[57] CLAIM

The ornamental design for a box for plants, flowers or the like, as shown and described.

DESCRIPTION

FIG. 1 is a side elevational view of a box for plants, flowers or the like showing my new design, all sides being identical;

FIG. 2 is a bottom plan view thereof;

FIG. 3 is a top plan view thereof; and

FIG. 4 is a fragmentary sectional view taken in the direction of the arrows on line 4—4 of FIG. 3.

FIG. 1

FIG. 3
